(57) **CLAIM**

We claim the ornamental design for a receptacle, substantially as shown and described.

DESCRIPTION

FIG. 1 is a perspective view of the receptacle according to an exemplary embodiment.

FIG. 2 is a side elevation view of the receptacle.

FIG. 3 is a front elevation view of the receptacle; and, FIG. 4 is a top plan view of the receptacle.

The broken lines immediately adjacent the shaded areas represent the bounds of the claim and all other broken lines are for illustrative purposes only. None of the broken lines form a part of the claimed design.
